UNITED STATES PATENT OFFICE.

HARRY V. BALL, OF CONCORD, MASSACHUSETTS, ASSIGNOR TO R. HOE & CO., INC., OF NEW YORK, N. Y., A CORPORATION OF NEW YORK.

COMBINED GEAR GUARD AND STEP.

Application filed May 27, 1925. Serial No. 33,096.

This invention relates to certain improvements in a combined gear guard and platform particularly adapted for printing machines.

5 In large multi-deck printing mechanisms or in printing machines in which the cylinders are of considerable height above the floor, it is necessary for the pressman to climb above the machines for dressing the 10 plate cylinders or for making any required adjustments in the inking and the other mechanisms. These machines are gear driven, and it is necessary that these gears be guarded or protected so as not to involve 15 the pressman in danger of being caught in the gears.

Heretofore it has been customary to use steps projecting out sideways from the machine, which the pressman used in climbing 20 around the different parts of the mechanisms, and, in some instances, these projecting steps were in the way of other mechanisms, or were difficult to install in the desired location owing to the confined space in the press room.

25 It is a special object of the present invention to provide a combined gear guard and platform on which the pressman may stand while performing his duties around the machine, thus doing away with parts projecting 30 beyond the gears.

With this and other objects not specifically referred to in view, the invention consists in certain novel parts, arrangements and combinations which will be described in connection with the accompanying drawings and the novel features pointed out in the 35 claims hereunto annexed.

Referring to these drawings,—

Figure 1 is an end elevation, partly in section and partly broken away, of so much of a printing machine as is necessary for an understanding of the invention;

Figure 2 is a sectional plan view taken on the broken line 2—2 of Fig. 1;

45 Figure 3 is a detail sectional view taken on the line 3—3 of Fig. 1, and

Figure 4 is a detail sectional view taken on the line 4—4 of Fig. 1.

Referring now to these drawings, the invention has been illustrated as used with a 50 printing machine, a portion of one deck only being shown, it being understood that one of the combined guards and platforms will be provided about the machine where necessary or required. As shown, there is illustrated a

perfecting couple including a form cylinder 1, an impression cylinder 2, and a perfecting couple including a form cylinder 3 and its impression cylinder 4, these cylinders being carried on shafts 5, suitably mounted in side frames 6, of any usual or suitable configurations. The form cylinders are inked from the usual distributing cylinders 7 and trains of ink rolls 8. The cylinders are, in the particular machine shown, arranged in line, and these cylinders are driven through a train of gears from the form cylinder 1. To effect this, the shaft 5 is provided with a driving gear 9 which is in mesh with a gear 10 on the shaft 5 of the impression cylinder 2. This 60 shaft also carries, inside the gear 10, a gear 11 which is in mesh with a gear 12 on the shaft 5 of the impression cylinder 4. This shaft also carries a gear 13, outside the gear 12, which is in mesh with the gear 14 on the 65 shaft 5 of the form cylinder 3.

In accordance with the invention, a guard is provided for these gears which is formed so as to also act as a platform on which a press operator may stand. The guard, therefore, is made strong and rigid so as to bear the weight to which it would be subjected. While the guard may be of various configurations, in the particular construction shown the guard is in the form of a plate of metal having sides 15, 16, and a front 17. The front piece of the guard is cut away so as to lighten the construction, except for certain portions which extend over and protect the gear teeth, as shown in Fig. 1 and the top of the guard 70 is formed with a flat surface 18 which provides a platform. The guard may be held in place in any suitable manner. In the particular construction illustrated, the guard is secured to the side frames 6, before referred to, at each end, by means of a plate 19, this plate being bolted to the guard and to the frames by bolts 20.

The guard plate is also secured intermediate its ends so as to afford a very rigid structure. In the particular construction illustrated the guard is provided with interior thickened portions 21 to which are bolted legs 22 of L-shaped brackets 23, the vertical legs of these brackets being bolted to vertical frames 24 of the press. To remove the guard to get access to the gears, it is necessary only to remove the bolts by which the guard is secured in place.

With the construction shown and de- 110

scribed, a very strong rigid construction is provided, which effectively guards a train of gears and at the same time affords a strong platform or step on which the press operator can stand while performing his duties about the press. While the guard shown has been found effective in practice, it will be understood that changes in the shape of the guard and in the method of securing it in place may 10 be made without departing from the invention as defined in the appended claims.

What I claim is:

1. The combination of a plurality of cylinders arranged in line, intermeshing gears on 13 the cylinders at one end thereof for driving them, a casing over the gears hav-

ing a wide flat top providing a platform on which an operator may walk along the line of cylinders, and means for securing the casing in position.

2. The combination of a plurality of cylinders arranged in line, intermeshing gears on the cylinders at one end thereof for driving them, a casing over the gears and shaped to conform with the shape of the gears and having a wide flat top providing a platform on which an operator may walk along the line of cylinders, and means for rigidly securing the casing in position.

In testimony whereof, I have hereunto set 30 my hand.

HARRY V. BALL.
